UNITED STATES PATENT OFFICE.

VOJTECH PUC, OF PRAGUE-VINOHRADY, BOHEMIA.

POLISHING MACHINE.

1,415,478.

Specification of Letters Patent.

Patented May 9, 1922.

Application filed February 6, 1920. Serial No. 356,783.

To all whom it may concern:

Be it known that I, VOJTECH PUC, a citizen of the Republic of Czecho-Slovakia, residing at Prague-Vinohrady, in Bohemia, have invented certain new and useful Improvements in Polishing Machines, (for which I have filed applications in Austria Apr. 5, 1918, and in Germany Apr. 5, 1918,) of which the following is a specification.

10 This invention relates particularly to machines for polishing relatively short lengths of wire or rods of small diameter, such as are used for making safety-pins, knitting needles, crochet needles, etc.

15 It is important that such wires or rods should be thoroughly cleaned or polished before they are given final shape or nickel-plated. When the wires or rods are used to form pointed articles such points are made

20 by suitable grinders or other tools or machines before the wires or rods are polished and after the polishing operation the wires are bent or otherwise formed into the desired shape and are then nickel-plated, black-varnished, or otherwise treated.

25 My present invention does not involve any mechanism for cutting the wires or bending them into shape or for pointing them, but relates to a new form of machine for polishing the wires in such manner as to remove all rust and other such imperfections therefrom so that the wires may be properly plated and shall be perfectly smooth and even. The wires are polished after they 30 have been pointed, and while my machine is especially designed for polishing wires or rods from which safety-pins, knitting needles, etc., are made, it may be employed for polishing wires, rods and the like, suitable 35 for making other articles.

40 In carrying out my invention I provide a container for a large number of wires or rods which is revolved in such manner as to cause the wires to tumble over each other and rub the one on the others to thus produce an abrading action which serves to clean the wires. Preferably ground emery or other abrading material is introduced in the container or into the mass of wires to 45 assist the polishing operation. Means is provided for revolving the container and in order that the wires may be held in close contact with each other and to assist in re-

volving them, I provide a toothed roller which bears on the top of the mass of wires 55 and this roller is rotated in a direction opposite to that in which the container moves. Preferably this roller is made adjustable across the mass of wires in order that it may be made to bear on their pointed ends 60 and thus cause the wires to assume an angle which will bring the pointed or tapered ends together or in contact with each other in such manner as to cause them to rub against each other and thus produce the desired 65 abrading action. In order to prevent the wires from being unduly bent or depressed in the container, I provide means below the wires for supporting them while being revolved.

70 Other features of my invention will be hereinafter described.

In the accompanying drawings:—

Figure 1 shows a front elevation of a 75 polishing machine embodying my invention.

Figure 2 shows an end elevation thereof, looking at the left-hand end of the machine.

Figure 3 shows a section on the line 3—3 of Figure 4, illustrating particularly the container for the wires, the toothed pressure 80 roller, which operates on the top of the wires and the pressure roller which supports the wires from beneath.

Figure 4 is a section on the line 4—4 of Figure 1 and illustrates clearly how the 85 wires are supported in the container and how they are operated on by the toothed roller arranged above them.

Figure 5 is a detail plan view, showing the toothed roller which bears on the top of 90 the wires and also the frame which supports the roller and the mechanism for turning the roller.

Figure 6 is a detail view in side elevation of the supporting or pressure roller operating 95 below the wires.

Figure 7 is a plan view thereof.

Figure 8 is a detail view in longitudinal section of the container and illustrates how the toothed pressure roller may be shifted 100 to one side of the container to operate more efficiently on the pointed ends of the wires.

The supporting frame may be of any suitable construction. As shown, it comprises end frames A, A', connected by tie rods a. 105 On the supporting frame are mounted two

parallel longitudinally arranged channel bars B, B', which serve to support the mechanism hereinafter described.

On the frame I mount standards C', C², 5 provided with bearings for three longitudinally arranged shafts D', D², D³. The shaft D' carries fast and loose pulleys E', E², and the shaft D' has keyed to it a spur-wheel d, which meshes with a similar wheel 10 d', keyed to the shaft D². The spur-wheel d also meshes with a similar wheel d², keyed to the shaft D³. The shafts D', D² and D³ are revolved in the direction indicated by the arrows.

15 The container for the wires to be polished comprises two flanged disks G, having hubs g, carrying set screws g', by means of which the disks may be secured to the shaft D² and set any desired distance apart thereon. 20 The flanges g² of the disks extend inwardly towards each other from the peripheries of the disks and these flanged disks are of the same diameter and serve to support the wires or rods X in the manner illustrated 25 most clearly in Figure 3. It will be observed that the disks are arranged a considerable distance from each other and support the wires at their ends only, there being a clear space between the disks so that 30 the wires may be readily introduced into the container. If necessary, the set screws g' may be loosened and the disks moved apart to receive the wires and then brought closer together. A large quantity of wires 35 or rods may be supplied to the container and these wires or rods are arranged in the manner illustrated, i. e., they are parallel and mutually support each other. The container is not completely filled, but a very 40 large number of wires may be accommodated.

As the container is revolved, the wires tumble over each other and revolve about their own axes and the operation is such 45 as to clean and polish the wires. This action may be increased by supplying emery powder or other abrading material, which is passed into the wires while they are being revolved.

50 In order to assist in the polishing operation, I provide a toothed roller H, which is attached to a shaft h, carried by a frame L, supported on the shaft D³. The roller H is provided with a hub, h', carrying a set 55 screw h², by means of which the roller is secured to the shaft and may be set at any desired point lengthwise thereon.

The frame L, which carries the toothed pressure roller H, comprises two arms l, 60 provided at their inner ends with bosses l', through which the shaft D³ extends and at their opposite ends with a cross piece l².

The shaft D³ revolves freely in the bosses and the frame may be raised or lowered or 65 swung on the shaft to the desired extent.

Collars l⁴ are held on the shaft D³ by set screws l⁵. These collars may be adjusted endwise on the shaft and set to hold the frame L against endwise movement on the shaft while permitting it to swing freely 70 thereon.

The shaft h, which is supported in the frame L, carries a spur-wheel M, the hub m of which is secured to the shaft h by a set screw m'. The spur-wheel M engages a 75 similar wheel N, secured to the shaft D³ and held in place by a set screw n', carried by the hub n. The arrangement is such that the toothed roller H is revolved in a direction contrary to that of the container G, as 80 indicated by the arrows.

The toothed roller H is a pressure roller and the desired amount of pressure is obtained by an adjustable weight O, carried by a rod o, projecting from the frame L. 85 The teeth z on the roller H are preferably of the shape clearly illustrated in Figure 4.

In order to assist in the operation I may secure rigidly to the shaft D², between the flanged disks G, one or more small toothed 90 sleeves Q which operate on the wires in the middle portion of the mass to stir or disturb them and to thus cause the wires to exert an abrading action on each other.

It will be observed by reference to Figure 95 8 that the pressure roller H may be shifted to one side of the container so as to bear on the pointed ends of the wires in such manner as to cause them to assume an angle which will bring the pointed or tapered ends together or in contact with each other in such manner as to cause them to rub against each other and thus produce the desired abrading action.

100 The pressure roller H bearing on the top of the wires may tend to bend them unduly and in order to counteract this tendency I provide a pressure roller S, which supports the wires between the disks. This roller is carried by a horizontally arranged frame T, pivoted to the main frame at t and carrying a weight U, which may be adjusted to cause the roller to bear on the wires with the desired degree of pressure. In order to hold 105 the frame against vertical movement when desired, I provide a spring bolt V, which is supported on the machine frame and engages the frame T in the manner clearly shown. This bolt may serve to hold the roller S away from the wires if desired, but 110 serves mainly to hold the roller against vertical movement when there are no wires in the container.

I have shown by full lines in Figure 1 a single pair of disks constituting a container 115 and devices cooperating therewith for polishing a mass of wires, but the same driving mechanism may, if desired, be employed to actuate a plurality of such devices.

The machine herein illustrated and de- 130

scribed has been operated most efficiently to thoroughly clean and polish large quantities of wires and rods in the manner specified, and it possesses the elements of novelty hereinafter claimed.

I claim as my invention:—

1. A polishing machine comprising a container for the articles to be polished, means for rotating the container, a toothed roller journaled outside the container extending thereto and bearing on the articles, and means for rotating said roller.

10 2. A polishing machine comprising a container for the articles to be polished, means for rotating the container, a toothed roller journaled outside the container and operating above the articles therein, means for rotating said roller, and a roller operating in the container below the articles.

15 3. A polishing machine comprising a container for the articles to be polished, means for rotating the container, means supported outside the container operating therein and bearing on the articles to hold them in contact with each other, and a toothed device arranged centrally in the container in line with its axis of rotation and operating on the articles.

20 4. A polishing machine comprising a container for the articles to be polished, means for rotating the container, a roller journaled outside the container extending thereto and bearing on the articles, means for rotating said roller, and a plurality of toothed devices arranged centrally in the container and operating on the articles in the middle portion of the mass.

25 5. A polishing machine comprising a container for the articles to be polished, means for rotating the container, a toothed roller journaled outside the container extending thereto and bearing on the articles, means for rotating said roller, and a toothed device arranged centrally in the container and operating on the articles.

30 6. A polishing machine comprising a container for the articles to be polished, means for rotating the container, a toothed roller journaled outside the container extending thereto and bearing on the articles, means for rotating said roller, and means for raising and lowering the roller.

35 7. A polishing machine comprising a container for the articles to be polished, means for rotating the container, a toothed roller operating in the container and bearing on the articles, a frame in which the roller is supported, means for raising and lowering the frame, and means for rotating the roller.

40 8. A polishing machine comprising a container for the articles to be polished, means for rotating the container, a toothed roller operating in the container and bearing on the articles, means for rotating said roller,

45 a roller operating in the container below the articles, and a counterweighted frame in which said roller is mounted.

9. A polishing machine comprising a container for the articles to be polished, means for rotating the container, a toothed roller operating in the container above the articles, means for rotating said roller, a roller operating in the container below the articles, a pivoted frame in which said roller is mounted, an adjustable counterweight carried by said frame, and devices for holding the frame in locked position.

10. A polishing machine comprising a container for the articles to be polished, consisting of two opposed flanged disks connected for conjoint operation but having a free space between the inner edges of their flanges, means for rotating said container, and a roller operating in the container above the articles therein.

15 11. A polishing machine comprising a container for the articles to be polished, consisting of two opposed flanged disks spaced apart and adapted to support the articles to be polished and which are connected for conjoint operation, means for rotating the container, a toothed roller operating in the container above the articles therein, and means for rotating said roller.

20 12. A polishing machine comprising a container for the articles to be polished, consisting of two opposed flanged disks connected for conjoint operation with a space between them, means for rotating said container, a toothed roller operating in the container above the articles therein, means for rotating said rollers, and means for raising and lowering the roller.

25 13. A polishing machine comprising a container for the articles to be polished, means for rotating the container, and a device supported outside the container extending thereto and bearing on the pointed or tapered ends of the articles to be polished.

30 14. A polishing machine comprising a container for the articles to be polished, means for rotating the container, and a toothed roller journaled outside the container extending thereto and bearing on the tapered ends of the articles to be polished.

35 15. A polishing machine comprising a container for the articles to be polished, means for rotating the container, a device operating in the container and bearing on the articles to be polished, and means for adjusting said device lengthwise of its axis to cause it to bear on any desired part of the mass of articles.

40 16. A polishing machine comprising a container for the articles to be polished, means for rotating the container, a toothed device arranged centrally in the container and operating on the articles, a toothed device operating in the container and bearing

45 130

on the articles, and means for adjusting said toothed device lengthwise of its axis to cause it to bear on any desired part of the mass of articles being treated.

5 17. A polishing machine comprising a container for the articles to be polished, means for rotating the container, a toothed roller operating in the container and bearing on the articles to be polished, means for 10 rotating said roller, and means for adjusting it lengthwise of its axis.

15 18. A polishing machine comprising a container for the articles to be polished, consisting of two opposed flanged disks connected together for conjoint operation, means for rotating said container, a toothed roller operating in the container above the articles therein, means for adjusting the disks towards and from each other, a frame 20 in which the toothed roller is supported, means for raising and lowering said frame, means for rotating the toothed roller, and means for adjusting the roller longitudinally of its axis.

19. A polishing machine comprising a 25 container for the articles to be polished, means for rotating the container, a toothed roller operating in the container and bearing on the articles, means for rotating said roller, a frame in which the roller is supported and which is adapted to swing in a vertical plane, and an adjustable counter-weight carried by said frame.

30 20. A polishing machine comprising a 35 container for the articles to be polished, consisting of two opposed flanged disks connected for conjoint operation adjustable towards and from each other and having a clear space between them, means for rotating said container, a roller operating in the 40 container above the disks and between them, means for rotating the roller, and means for adjusting the roller in opposite directions towards and from the disks.

45 In testimony whereof, I have hereunto subscribed my name.

VOJTECH PUC.
